(57) **CLAIM**

I claim the ornamental design for a combined storage container and lid, as shown and described.

DESCRIPTION

FIG. 1 is a top perspective view of a combined storage container and lid according to a first embodiment;

FIG. 2 is a bottom perspective view of the combined storage container and lid of FIG. 1;

FIG. 3 is a front elevational view of the combined storage container and lid of FIG. 1;

FIG. 4 is a right side elevational view of the combined storage container and lid of FIG. 1;

FIG. 5 is a back elevational view of the combined storage container and lid of FIG. 1;

FIG. 6 is a left side elevational view of the combined storage container and lid of FIG. 1;

FIG. 7 is a top plan view of the combined storage container and lid of FIG. 1;

FIG. 8 is a top perspective view of a combined storage container and lid according to a second embodiment;

FIG. 9 is a bottom perspective view of the combined storage container and lid of FIG. 8;

FIG. 10 is a front elevational view of the storage container and lid of FIG. 8;

FIG. 11 is a right side elevational view of the combined storage container and lid of FIG. 8;

FIG. 12 is a back elevational view of the storage container and lid of FIG. 8;

FIG. 13 is a left side elevational view of the storage container and lid of FIG. 8; and,

FIG. 14 is a top plan view of the combined storage container and lid of FIG. 8.
